United States Patent Office

Des. 180,944
Patented Sept. 10, 1957

180,944

LABORATORY CLAMP OR SIMILAR ARTICLE

Frank P. Fritchle, Santa Ana, Calif., and Manning S. Reynolds and Earl K. Takata, Chicago, Ill., assignors to Central Scientific Co., Chicago, Ill., a corporation of Illinois

Application October 23, 1956, Serial No. 43,466

Term of patent 14 years

(Cl. D54—11)

Fig. 1.

Fig. 2.

Fig. 4.

Figure 1 is a perspective view of a laboratory clamp or similar article showing our new design;

Figure 2 is a front view of the article as shown in Figure 1;

Figure 3 is a bottom plan view of the article as shown in Figure 1; and

Figure 4 is a right hand end view of the article as shown in Figure 1.

The dominant features of the design reside in the portions shown in full lines.

We claim:

The ornamental design for a laboratory clamp or similar article, substantially as shown and described.
